ELECTROMAGNETIC VIBRATORY DEVICE

James Samuel Paterson Roberton, London, England, assignor to International Standard Electric Corporation, New York, N. Y., a corporation of Delaware

Application August 7, 1947, Serial No. 767,241
In Great Britain June 21, 1946

Section 1, Public Law 690, August 8, 1946
Patent expires June 21, 1966

13 Claims. (Cl. 179—114)

1

This invention relates to electro-acoustic transducers, and more particularly though not exclusively to telephone receivers.

Such devices have commonly consisted of a magnetic metal diaphragm on one side of which were placed pole pieces co-operating with a permanent magnet, such pole pieces being surrounded by operating coils.

It is well known in the design of electro-acoustic transducers of this type that the sensitivity is proportional to the product of the polarising flux density in the main air gap between pole pieces and the diaphragm, multiplied by the square root of the effective permeability of the diaphragm by voice frequency fluxes, and therefore tends to increase as the steady magnetic flux in the said air gap is increased.

This tendency is, however, opposed by the tendency of the diaphragm to become saturated by the steady flux so that its permeability is reduced to alternating fluxes corresponding to the sounds. A limit of sensitivity is thus set for any given combination of diaphragm and magnet system.

In designs of electro-acoustic transducers commonly adopted in the past the ratio of fluxes in the air gap or air gaps between the diaphragm and the pole pieces of the magnetic system on the one hand and that in the material of diaphragm, on the other hand, has been limited to unity, since both fields follow the same orbit, when leakage effects are ignored.

It has been found that the sensitivity which can be obtained, for any given limiting design conditions, can be increased when the steady magnetic flux in the said air gaps has a component which does not pass through the material of the diaphragm itself or where it has components passing through different parts of the material of the diaphragm.

According to one of its aspects the invention consists of an electro-acoustic transducer having a diaphragm, a single permanent magnet member, one or more pole-pieces one end of such pole-piece, or of each of them if more than one, being adjacent to the diaphragm and forming one or more gaps respectively between the said one or more pole-pieces and the diaphragm, such one or more pole-pieces co-operating with the said permanent magnet member to produce a magnetic flux in such one or more gaps, and having also an additional pole or pole-pieces co-operating with the said permanent magnet member whereby not all of the flux which traverses the said one or more gaps traverses that part or those parts of the diaphragm which such flux would traverse.

2 in the absence of the said additional pole-piece or pole-pieces.

According to another of its aspects, the invention consists of an electro-acoustic transducer having a diaphragm and a single permanent magnet member, in which the magneto-motive force of the said permanent magnet member causes a polarising flux in one or more gaps between the diaphragm on the one hand and the said permanent magnet member or one or more pole-pieces co-operating therewith on the other hand, and in which a portion of the said magneto-motive force is used to divert polarising flux from a part or parts of the diaphragm through which all the polarising flux in the said one or more gaps would otherwise pass.

According to another of its aspects, the invention consists of an electro-acoustic transducer having a diaphragm of magnetic material, a single permanent magnet member, one or more pole-pieces, and one or more additional pole pieces, the first mentioned one or more pole pieces approaching near to the diaphragm so as to form one or more air gaps between the said one or more first mentioned pole pieces and one part of the diaphragm, and the said additional one or more pole pieces co-operating with the said permanent magnet member to provide an additional magnetic circuit so that the ratio between the total magnetic flux in the air gap or air gaps between the diaphragm and the first mentioned one or more pole pieces on the one hand, and the flux in that part or those parts of the diaphragm which would be traversed by magnetic flux were the said additional one or more pole pieces to be removed, on the other hand, may be increased above unity, the former flux being the greater.

According to another of its aspects the invention consists of an electro-acoustic transducer having a diaphragm of magnetic material, a single permanent magnet member, one or more pole pieces (hereinafter called the "main pole system"), and one or more additional pole pieces (hereinafter called the "auxiliary pole system"), the said permanent magnet member co-operating with the main pole system to produce a magnetic flux in one or more air gaps (hereinafter called "the main gap system") between the main pole system and one part of the diaphragm and the auxiliary pole system co-operating with the permanent magnet member to produce an additional magnetic flux in the main gap system so that only a part of the flux in the main gap system traverses that part or parts of the diaphragm which would

be traversed by the flux in the main gap system in the absence of the auxiliary pole system.

In certain practical embodiments of the invention the additional flux produced by the auxiliary pole system, is applied so that it traverses a gap or gaps, hereinafter called the "auxiliary gap system," between the auxiliary pole system and the diaphragm, which is substantially opposite to the main gap system and on the other side of the diaphragm so that the additional fluxes flow in the main gap system and the auxiliary gap system without traversing any part of the diaphragm laterally (i. e. along courses in the plane of the diaphragm). Alternatively such additional flux can be caused to take a different path through the diaphragm from that taken by the flux arising from the main pole system so that no single part of the diaphragm carries the whole of both fluxes.

Certain embodiments of the invention will now be described in relation to the attached drawings in which:

Fig. 1 is a diagram of one embodiment of the invention in cross section

Fig. 2 is a diagram of another embodiment of the invention in cross section

Fig. 3 is a diagram of another embodiment of the invention in cross section

Fig. 4 is a circuit diagram representing an electrical analogy of the magnetic systems of the embodiments shown in Figs. 1, 2 and 3.

The embodiments in these figures have a pole piece of one polarity, representing the main pole system and such arrangement is hereinafter called a "monopolar" arrangement.

Fig. 5 is a diagram of an embodiment of the invention having two pole pieces of opposite polarity representing the main pole system and such an arrangement is hereinafter called a "bipolar" arrangement.

Fig. 6 is a circuit diagram representing an electrical analogy of the magnetic system of the embodiment shown in Fig. 5.

Fig. 7 is a diagram of a second bipolar embodiment of the invention.

Fig. 8 is a circuit diagram representing an electrical analogy of the embodiment shown in Fig. 7.

Fig. 9 is a diagram of a third bipolar embodiment of the invention.

Fig. 10 is a circuit diagram representing an electrical analogy of the embodiment shown in Fig. 9.

Fig. 11 is a diagram of a fourth bipolar embodiment of the invention.

Figs. 12, 13 and 14 are top view, transverse cross section and bottom view, respectively of a telephone earpiece capsule following the arrangement shown diagrammatically in Fig. 1.

In Fig. 1 a cylindrical magnet 1 and a diaphragm 2 of magnetic material are arranged so that the diaphragm lies within the magnet a little distance from and in a plane parallel to that of one end face of the magnet. The magnet is polarised axially, one end face being of north polarity and the other end face of south polarity. Across the end face of the magnet furthest from the diaphragm lies an end plate 3 supporting a single cylindrical pole piece 4 around which are operating windings 5. Plate 3 and pole piece 4 are the main pole system. A plate 6 rests on the other end face of the magnet and is dished in the centre so as to approach close to the diaphragm opposite pole piece 4, but on the other side of the diaphragm therefrom.

Plate 6, which constitutes the auxiliary pole

system, is pierced by a single hole in the centre for the ingress or egress of sound. It is possible of course for the depressed central portion to present a disc-like face to the diaphragm and for the sound aperture or apertures to be located elsewhere on the plate.

In Fig. 2 corresponding reference numerals to those used in Fig. 1 are used to denote corresponding things. A round bar magnet 1 polarised axially, stands in the bottom of a cup 8 of permeable magnetic material. A pole piece 4, similar to pole piece 4 in Fig. 1 stands on top of the magnet.

A member 7 of permeable magnetic material, in the form of a hollow truncated cone with an inward facing flange at its smaller end is fixed by this flange part way down the magnet, nearer to pole piece 4 than to cup 8. The conical member 7 extends in a direction away from the bottom of cup 8 and towards its larger end, which carries the diaphragm, so as to leave a gap between the centre of the diaphragm and pole piece 4. A member 6, similar to 6 of Fig. 1, may be turned over along its outer periphery so as to meet the upper rim of cup 8 or alternatively cup 8 could be extended upwardly and plate 6 could be as shown in Fig. 1.

In this arrangement pole piece 4 forms the main pole system as in Fig. 1, but the auxiliary pole system is constituted by cup 8 and plate 6.

Plate 6 in the Fig. 2 arrangement is capable of the same modifications of central pole face shape and sound aperture as are described in relation to Fig. 1.

In Fig. 3, a flat bar or disc magnet is used polarised from centre to ends or circumference respectively.

In the centre of magnet 1 the pole piece 4 is fixed and a cylindrical member 10, of permeable magnetic material rests, at two places on one of its end faces, on the outer ends of magnet 1. A plate 6, similar to plate 6 in Fig. 2, rests on the other end face of cylindrical member 10. Another member 9, of permeable magnetic material which may be a cylinder of a part or parts of a cylinder, of smaller diameter than member 10, rests on two places near the ends of magnet 1 and on the end face or faces furthest from magnet 1, the diaphragm is mounted so as to be placed a suitable distance from the end of pole piece 4 to form the main gap system.

Pole piece 4 and member 9 form the main pole system and cylindrical member 10 and plate 6 form the auxiliary pole system.

In Figs. 1, 2 and 3, the main gap system, is marked with the reference A, the auxiliary gap system with the reference E, the part of the magnet associated with the main pole system, by the reference V1, the part of the magnet associated with the auxiliary pole system by the reference V2 and the diaphragm by reference D.

In Fig. 4 an electrical analogy is represented using these letter references to identify the circuit element symbols.

V1 and V2 are represented by batteries equivalent to the magneto-motive forces of the respective parts of the magnet, A (the reluctance of the main gap system) by a resistance, E (the reluctance of the auxiliary gap system) by a resistance and D (the reluctance of the diaphragm) by a resistance.

V3, a source of alternating current, represents the alternating magneto-motive forces corresponding to the sounds to be transduced.

The application of network analysis to Fig. 4 would reveal a somewhat complex pattern of currents flowing in the various elements of the circuit but the general effect of the arrangement is that the total steady current in A is the sum of the steady currents in E and D, and only the latter passes through the diaphragm laterally (that is to say in a direction parallel to the diaphragm surface) so as to saturate it.

The alternating currents in the system are also partially diverted through E and V₂ which causes some loss but not in proportion to the gain resulting from the increased current in A as compared with the maximum feasible figure for this in the conventional type of electro acoustic transducer.

The matter can be viewed from another standpoint without recourse to the electrical analogy. It is well known that the efficiency of an electro-acoustic transducer of the type having an armature of magnetic material is proportional to the product of the steady polarising flux density in the gap between the armature and the magnet or pole pieces co-operating therewith, multiplied by the square root of the permeability to alternating fluxes, of the magnetic circuit as a whole. Where the diaphragm itself constitutes the armature, this magnetic circuit will include the diaphragm and an air gap or air gaps between the latter and the magnet or pole pieces.

Increasing the polarising flux density in the said gap or gaps beyond a certain point tends to reduce the permeability to alternating fluxes, of the magnetic circuit, due to saturation of the diaphragm by the polarising flux, and the maximum efficiency for any given design will be attained when the said permeability to alternating fluxes is somewhat below its maximum value, since the rise of the polarising flux density is more influential in the product than the said permeability since only the square root of the latter is concerned in the product.

The point at which it ceases to be of advantage to increase the polarising flux beyond that giving the maximum value of permeability of the magnetic system to alternating fluxes will generally depend upon the saturability of the diaphragm since this is usually the most readily saturable part of the magnetic circuit.

In the arrangements of Figs. 1, 2, 3 and 4 the polarising flux in the main gap system may be increased beyond the normal optimum, since the additional polarising flux, not traversing the diaphragm, does not affect its permeability to alternating fluxes and a higher product of the said flux and the square root of the said permeability is obtained, giving increased efficiency.

The vibrational forces acting on the diaphragm from the auxiliary gap system oppose those from the main gap system but not to the same degree as the increase in the latter, and there is a considerable net gain in efficiency.

It is generally advisable, to arrange for the polarising flux in the auxiliary gap system to be smaller than that in the main gap system to avoid mechanical instability of the diaphragm which might arise if it were pulled in opposite directions by two opposing and nearly equal polarising magneto-motive forces.

Advantage may be taken of the improvement in a number of ways of course, when an electro acoustic transducer is being designed ab initio. For instance, normal proportions may be chosen for all parts but the permanent magnet the latter being made larger by the amount necessary to provide the additional polarising flux.

Alternatively, if it were required for any reason to use a smaller or thinner diaphragm, some of the usual disadvantages of smaller and thinner diaphragms could be avoided by the use of a normal sized magnet, only part of which applied steady flux to the diaphragm material, the rest of the magnet being utilised to produce that part of the total fluxes not traversing the diaphragm.

The same principles can be applied to bipolar types of electro acoustic transducer and Figs. 5 to 11 illustrate several such types.

Fig. 5 illustrates diagrammatically the magnetic circuit of a bipolar electro acoustic transducer having a magnet 11, polarised longitudinally, and with pole pieces 12 and 13 attached to its two ends and extending to the axis of the magnet towards a diaphragm 14, so as to leave a gap between each pole piece and the diaphragm. These gaps form the main gap system.

Additional pole pieces 15 and 16 are attached to intermediate points along the length of the magnet, equidistant from the ends and 15 and 16 extend away from the magnet being shaped to pass round the edge of the diaphragm and bent over so as to approach the diaphragm on the other side from the pole pieces 12 and 13, leaving gaps between each of the pole pieces 15 and 16, and the diaphragm which are substantially opposite to the gaps of the main gap system. The gaps between 15 and 16 and the diaphragm form the auxiliary gap system.

The pole pieces 15 and 16 are crossed over so that 15 is of opposite polarity to that of 12, and 16 is of opposite polarity to that of 13.

Interconnected coils are wound round 12 and 13, in which flow alternating currents representing sounds.

The diaphragm is mechanically supported by means not shown.

Fig. 6 shows an electrical analogy of this arrangement the similar letter references denoting the various circuit elements, to those used in Fig. 4, except that the main gap system and auxiliary gap system each consist of two gaps instead of one, and are represented as two elements, A/2 and two elements E/2 respectively and the alternating current source is shown as two elements, V3/2.

These same references are also marked on Fig. 5 to denote elements of the magnetic circuit corresponding to the elements of the electrical analogy. In bipolar arrangements the fluxes traverse the part of the diaphragm between the points opposite the pole pieces of the main pole system.

Analysis of the currents flowing in the various parts of the circuit shows that the gaps, A/2, of the main gap system each carry current equal to the sum of the current flowing in D plus the current flowing in one of the gaps E/2 of the auxiliary gap system, that is to say greater than the current in D, so that the arrangement is similar in principle to the monopolar arrangement previously described.

Fig. 7 shows an extreme form of the arrangement of Fig. 5 and Fig. 8 shows an electrical analogy thereof. In these figures the same numerical and other references are used as those in Figs. 5 and 6, to indicate corresponding elements.

The pole pieces 15 and 16 are here connected across the whole of magnet 11 and in order that the forces acting on the diaphragm from the direction of the main gap system shall predominate

over those from the direction of the auxiliary gap system, the desirability of which has been explained, it is necessary to have wider gaps for the auxiliary gap system, than for the main gap system.

Figs. 9 and 10 in which the same numerical references as those used in Figs. 5 and 6, are used to denote corresponding elements, show respectively another bipolar arrangement and an electrical analogy of the magnetic system thereof.

The magnet 11 is magnetised with consequent polarity along its length. The pole pieces 12 and 13 of the main pole system are in contact with intermediate parts of the magnet substantially equidistant from adjacent ends of the magnet and the pole pieces 15 and 16 of the auxiliary pole system are in contact with the ends of the magnet.

The polarisation of the magnet is such that the central portion between the points of contacts with pole pieces 12 and 13 is of opposite polarity to that of the two ends, which themselves are polarised in the same direction as one another. The polarity of the various points will therefore be such that one end will be, say, of north polarity, the intermediate portion in contact with the adjacent pole piece of the main pole system will be of south polarity, the portion in contact with the other pole piece of the main pole system will again be of north polarity and the other extreme end of the magnet will be of south polarity.

The pole pieces 15 and 16 are carried round the edge of the diaphragm and brought into proximity with the side of the diaphragm opposite to the side in proximity with pole pieces 12 and 13 but are not crossed over as in Figs. 5 and 7, since the polarisation of the magnet produces the same effect without this crossing over.

As compared with Figs. 5 and 7, the magnet must be longer for the arrangement of Fig. 11 since the magneto motive force V_1 is furnished by that of the two outer sections, opposed by that of the middle portion.

On the other hand, the fluxes of the auxiliary gap system traverse the outer portions of the magnet only and the fluxes of the main gap system traverse the middle portion of the magnet only and no part of the magnet is traversed by both fluxes. In Figs. 5 and 7 however, both fluxes traverse, in the former, part, and in the latter, the whole of the magnet so that the magnet in these figures must be of greater cross section than in the case of Fig. 9.

The electrical analogy illustrated in Fig. 10 shows that the arrangement of Fig. 9 is the same in principle as those of Figs. 5 and 7, in that currents passing in gaps A/2 of the main gap system are greater than those in D by the amount of currents flowing in gaps E/2 of the auxiliary gap system, showing that the polarising flux in the main gap system may be made greater than that which traverses the diaphragm.

The arrangement shown in Fig. 11 is a variant of that in Fig. 9, differing therefrom in having pole pieces 15 and 16 extended from the ends of the magnet into proximity with the outer edge of the diaphragm. The electrical analogy of Fig. 10 may be applied to the arrangement of Fig. 11 by considering the elements E/2 as representing the reluctance of the outer portions of the diaphragm in series with the gaps 17 and 18 between pole pieces 15 and 16 respectively, and adjacent parts of the outer edge of the diaphragm. These gaps 17 and 18 may be omitted and the

diaphragm brought into contact with pole pieces 15 and 16, since in any event, the reluctance of such gaps is likely to be small compared with that of the outer portion of the diaphragm.

Here the total flux passes through the diaphragm material but the different components of the flux traverse different parts of the diaphragm, no single part of which is traversed by the whole flux. Saturation of the diaphragm between the parts adjacent to the gaps of the main gap system is thus avoided as with the other arrangements described.

Figs. 12, 13 and 14 are top plan, side cross section and bottom plan respectively of a practical construction of an electro acoustic transducer of the type illustrated in Fig. 1, for use as a telephone earpiece insert.

The same numerical references are used in those figures as are used in Fig. 1, to denote corresponding elements.

A cylindrical magnet 1, polarised axially, has a base plate 3 seated on one end face and a top plate 6 seated on the other end face.

Fixed to the centre of base plate 3 is a cylindrical centre pole piece 4 carrying a bobbin 19 having windings, (not shown), to carry speech currents. Fitting closely within the magnet is a cylindrical spacing member 20, of an axial length less than that of the magnet. Member 20 must be of non magnetic material and if made of electrically conducting material, must not be a continuous ring since such a ring would act as a short circuited turn on the speech coil. One end of 20 rests on base plate 3, and on the other end face of 20 the diaphragm rests, being held in position by the pull of the polarising flux from pole piece 4.

The diaphragm edge is in proximity with the magnet at a part of the latter spaced away from the junction of the magnet and top plate 6.

Top plate 6 rests on the end face of the magnet remote from base plate 3, and between 1 and 6 is clamped a membrane 21 of impervious material, such as oiled silk, covering the diaphragm. The purpose of 21 is to keep moisture out of the interior of the receiver.

The central portion 22 of top plate 6 is dished inwards towards the diaphragm so as to present a disc-like pole surface thereto, substantially opposite to pole piece 4 on the other side of the diaphragm.

The sound apertures 23, four in number, are drilled into the sides of the depression in top plate 6.

The size and number of these holes should be chosen so that the acoustic mass of the plug of air within them in combination with the acoustic stiffness of the air space between plate 6 and the diaphragm forms an acoustically resonant system having a resonant frequency at the upper end of the frequency range which the transducer is required to handle. An acoustic arrangement of this type is described in British Patent No. 481,740. The flange of bobbin 19 nearest to the diaphragm approaches near to the diaphragm and part of the flange is reduced in thickness on the side nearest to the diaphragm so as to define an air space 24 between the diaphragm and the flange. This part of the flange is pierced with holes 25 communicating with a larger air space in the interior of the receiver, around the coils wound on the bobbin and bounded by spacing piece 20 and base plate 3. Spacing ring 20 is shown with an inward facing ledge upon which

rests the said flange of bobbin 19 completing the walls of the said larger air space.

The holes 25 are covered with porous material such as silk, to constitute an acoustic resistance between the small air space on one side of the said bobbin flange and the larger air space on the other side of it.

The dimensions of these air spaces and the holes 25 and the resistance material covering them are such that the acoustic stiffness of the air space, the acoustic mass of the plugs of air in the holes and the acoustic resistance of the material covering the holes combine to form a damped acoustically anti-resonant system over a range of frequencies including the natural mechanical resonant frequency of the diaphragm.

An acoustic system of this type is described in British Patent No. 503,676.

The base plate 3 is pierced with holes 26 through which the leads from the coil are passed, and a disc of insulating material 27 covers the base plate and has small holes concentric with holes 26, to keep the leads from touching 3.

A further disc of insulating material 28, carries two metallic contact pieces 29 and 30, each being connected to one of the leads from the coil, by eyelets 31.

The whole assembly is held together by a cylindrical covering 32 which projects beyond top plate 6 and disc 28, the projecting portions being pressed or spun over 6 and 28 to hold the components together axially.

I claim:

1. An electro-acoustic transducer comprising, in combination: a diaphragm of magnetic material; a single permanent magnet member; a main pole system including at least one pole piece adjacent said diaphragm and a longitudinal portion of said diaphragm magnetically connected in series with at least a portion of said permanent magnet member; a main air gap system including a main air gap between each pole piece and the adjacent part of said diaphragm, said permanent magnet cooperating with said main pole system to produce a magnetic flux in said main air gap system and an auxiliary pole system including a magnetic path having at least one pole piece adjacent said diaphragm and magnetically connected in series with at least a portion of said permanent magnet member, said magnetic path being connected in series with a main air gap and in shunt with the longitudinal portion of the diaphragm adjacent said main air gap, said permanent magnet cooperating with said auxiliary pole system to produce an additional magnetic flux in said main air gap system to divert a portion of said first-mentioned magnetic flux passing through said adjacent part of the diaphragm.

2. An electro-acoustic transducer as defined in claim 1, wherein said main pole system comprises a first pole piece mounted adjacent one side of said diaphragm, and said auxiliary pole system comprises another pole piece mounted adjacent the other side of said diaphragm.

3. An electro-acoustic transducer as defined in claim 2, wherein said other pole piece consists of a plate having a central recess so as to present a substantially circular disc-like pole face to said diaphragm.

4. An electro-acoustic transducer as defined in claim 3, wherein said pole piece plate is provided with apertures for the ingress and egress of sound.

5. An electro-acoustic transducer as defined in

claim 1, wherein said main pole system comprises a first pole piece mounted adjacent one side of said diaphragm, and said auxiliary pole system comprises a plate mounted adjacent the other side of said diaphragm, said plate having a central aperture provided with a lip, said lip presenting a substantially circular annular pole face to said diaphragm.

6. An electro-acoustic transducer as defined in claim 1, wherein said permanent magnet member is a round bar magnet polarized axially, said main pole system comprises a first pole piece mounted on and connected to one pole of said round bar magnet and arranged adjacent one side of said diaphragm, and said auxiliary pole system comprises another pole piece connected to the other pole of said magnet and arranged adjacent the other side of said diaphragm.

7. An electro-acoustic transducer as defined in claim 1, wherein said main pole system comprises two first pole pieces each of which is magnetically connected with an opposite pole of said permanent magnet and arranged adjacent said diaphragm, and said auxiliary pole system comprises two additional pole pieces each of which is magnetically connected with an opposite pole of said permanent magnet and arranged adjacent said diaphragm.

8. An electro-acoustic transducer comprising, in combination: a diaphragm of magnetic material; a single permanent magnet member; a main pole system including two pole pieces positioned adjacent one side of said diaphragm and each magnetically connected with an opposite pole of said permanent magnet member; a main air gap system including an air gap between each pole piece and the adjacent part of said diaphragm, said permanent magnet cooperating with said main pole system to produce a magnetic flux in said main air gap system and an auxiliary pole system including two additional pole pieces positioned adjacent the other side of said diaphragm and each magnetically connected with an opposite pole of said permanent magnet member, said permanent magnet cooperating with said auxiliary pole system to produce an additional magnetic flux in said main air gap system to divert a portion of said first-mentioned magnetic flux passing through said adjacent part of the diaphragm.

9. An electro-acoustic transducer as defined in claim 1, wherein said main pole system comprises two first pole pieces, each of which is magnetically connected with an opposite pole of said permanent magnet and arranged adjacent one side of said diaphragm, and said auxiliary pole system comprises two further pole pieces each of which is connected with an opposite pole of said permanent magnet and arranged adjacent the same side of the said diaphragm as the first pole pieces.

10. An electro-acoustic transducer comprising, in combination: a diaphragm of magnetic material; a single flat permanent magnet member magnetized with consequent polarity along its length; a main pole system including two pole pieces adjacent said diaphragm and each magnetically connected with first opposite poles of said permanent magnet member; a main air gap system including an air gap between each pole piece and the adjacent part of said diaphragm, said permanent magnet cooperating with said main pole system to produce a magnetic flux in said main air gap system and an auxiliary pole system including two additional pole pieces ad-

1 jacent said diaphragm and each magnetically connected with additional opposite poles of said permanent magnet member, said permanent magnet cooperating with said auxiliary pole system to produce an additional magnetic flux in said main air gap system to divert a portion of said first-mentioned magnetic flux passing through said adjacent part of the diaphragm.

11. An electro-acoustic transducer as defined in claim 1, wherein said permanent magnet is a flat magnet polarized longitudinally, said main pole system comprises two first pole pieces each of which is magnetically connected to an opposite pole of said magnet and arranged adjacent said diaphragm, and said auxiliary pole system comprises two additional pole pieces each of which is magnetically connected to parts of the magnet different from the parts to which the first pole pieces are connected and arranged adjacent said diaphragm in such manner that each of said additional pole pieces is nearest, at the end thereof adjacent said diaphragm, to that one of said first pole pieces from which it is furthest away at their respective connecting points with the permanent magnet, and in which the polarity of each additional pole piece is opposite to that of the one first pole piece which is nearest to it adjacent the diaphragm.

12. An electro-acoustic transducer as defined in claim 1, wherein said main pole system carries windings adapted to pass audio frequency currents, further comprising fixed external contact members, two plates mounted as an assembly in the same plane and each plate having portions concentric with portions of the other plate so that contact can be made with the two plates by means of said external contact members in

any position of rotation of said assembly in said plate about the axis of the aforesaid concentricity, each plate having one or more re-entrant portions so that connections at points which are equidistant from said axis can be made on said reentrant portions of both plates, and means for connecting the ends of said windings to said two plates respectively.

13. An electro-acoustic transducer as defined in claim 1, comprising a space which encloses a volume of air between said diaphragm and said auxiliary pole system, and apertures in the pole piece of said system, the dimension and shape of said space and apertures being such that the acoustic stiffness of the space combined with the acoustic mass of the air in the apertures provides an acoustically resonant system with a resonant frequency substantially at the upper limit of frequencies with which the transducer is adapted to deal.
